Dec. 522

Samuel H. Sailor of Philadelphia, Pa.

Assignor to

James G. Abbott & Archiles Lawrence of same place

Letters Patent No 522 Dated Nov. 9th 1852

The schedule referred to in these Letters Patent and making part of the same

To all whom it may concern:

Be it known that I, Samuel H. Sailor, of Philadelphia, in the County of Philadelphia and State of Pennsylvania, have invented or produced new and original designs in the plates of the stove called, "The Radiator," and do hereby declare, that the following is a full, clear and exact description of the same, reference being had to the annexed drawings, making part of this specification, in which

Figure 1, is the plan of the bed plate, with lettering complete, and something over one half of the ornamental portion shown, the remaining portion in outline, being a fac simile of that given.

XX are the outlines of the moulding from the point X, to the outer extreme X, figure 1.

X'X', the outlines of the same between the points X' and X'.

X"X", of the same, between the points X" and X" of the same figure.

2
Figure 2 is the plan of the top plate, all the letters complete; and nearly one half of the ornaments in finish, given; the remainder being lost, or repetition have only the outline.

$O' O.$ are the lines of section from the centre point, $O.$ to the outer edge O' on the dotted line.

$O'' O.$ the same from the point, $O.$ to the extreme edge at O'' .

$O''' O'''$ is the curved appearance of the under edge of the plate, from the corner O''' to the position O''' shown in figure 2.

Figure 3. is a plan of the grate plate, into which the sheet iron cylinder rests; part of the ornament is exhibited, the rest is in outline, it being the same all round.

Figure 4. is the elevation of the feed door, the right corner of the upper portion in outline, being similar in design to that on the left.

Figure 5. is the front elevation of one of the feet.

$z z.$ the lines of section, on the line $z z.$ figure 3.

$z'' z''$ the same from the centre, to the outer edge of the feed door, in the line $z'' z''$ fig 4. $z'' z''$ the same in the line $z'' z''$ figure 5.

Figure 6. is the plan of the base of the columns supporting the top of the stove.

The same letters refer to the same parts in all

the drawings.

The top plate (A) has around its edge, a moulding made up of the wavy curves (a), and the semi-spheres (b) combined as seen in the drawing; the under portion of the edge is of the wavy form seen at O''' figure 2. In the centre of the plate is the elevation (d), around the base of which are the mouldings (r), and the scrolls (c,c). At the summit of the elevation (d) is a moulding enclosing the tablet (e), which bears the inscription

"Abbot & Lawrence Patented 1852"

in sunken capitals and numerals, arranged as seen in the drawing. In the centre of the tablet (e) is the ornament (f), and upon the sides of the elevation are the

3
curled ornaments (d,d). In each of the corners of the plate, and proceeding from the central elevation (H) are the ornaments (f,f).

The bottom or bed plate (B) has around its edge a raised rim, consisting of the scrolls (h,h), around which are entwined the scrolls (g,g). In the centre of the front part is the crest (g'), supported by the scroll (h). Within the enclosure formed by the rim, is the inscription

"Abbott & Lawrence, Patented 1852"

in raised capitals and numerals, as seen in figure 1. At each of the corners are the ornaments (K) under which the feet are placed.

The outer edge of the grate plate is ornamented with the wavy and semi-spherical moulding (K') as seen in figure 3.

The feed door is convex, having the sunken panels, as seen in figure 4. It is surrounded by a frame (D) surmounted with the entwining scroll ornaments (Z,Z), similar to the rim (g,h) of the bed plate (B). Under the frame is the ornamental bracket (xx).

The foot (E) is composed of the scrolls (n) combined with the scales and other parts represented in figure 5.

The base (F) of the columns supporting the top of the stove, has the wavy and semi-spherical moulding (Z) similar to that on the edge of the grate plate (C).

What I claim as my invention or production and desire to secure by Letters Patent is the ornamental design of the top plate (A), the bed plate (B), the grate plate (C), the door frame (D), the foot (E), and the column base (F), of the stove called "the Radiator," as fully set forth and described in this specification and the annexed drawings.

In testimony whereof I have hereunto subscribed my name before two subscribing witnesses.
